UNITED STATES PATENT OFFICE.

MYLES F. MORAN, OF EAST LYNN, MASSACHUSETTS.

STRIP-WINDING MECHANISM AND REEL.

Application filed July 9, 1921. Serial No. 483,394.

To all whom it may concern:

Be it known that I, MYLES F. MORAN, a citizen of the United States, and resident of East Lynn, county of Essex, State of Massachusetts, have invented an Improvement in Strip-Winding Mechanisms and Reels, of which the following description, in connection with the accompanying drawing, is a specification, like characters on the drawing representing like parts.

This invention relates to improvements in strip winding mechanisms and reels for receiving and for delivering coiled strips of material, and the principal object thereof is to provide means for winding a strip of material, such as a moving picture film, in a suitable reel from the outside toward the center of the reel and also comprises means for transferring the wound spiral strip to a suitable strip delivering reel, means also preferably being provided for retaining the coiled strip upon the delivering reel.

Moving picture films are coiled upon a reel from the center outwardly and when placed in a moving picture machine are unreeled and passed across the projecting apparatus which throws the picture upon the film. After leaving the projecting apparatus the film has heretofore been coiled upon a second reel from the center outwardly. Thus the initial portion of the film begins at the center of the reel and necessitates the re-winding of the film in a reverse direction in order that the film may be in position to be again used in the moving picture machine. This entails a considerable amount of time and labor and produces more or less wear upon the film.

The principal object of the present invention is to provide means for winding the film upon a reel after it has passed through the projecting apparatus of the moving picture machine beginning at the outside and winding toward the center of the reel, so that the film is in condition to be at once

used in the moving picture machine without the necessity of re-winding. By thus avoiding re-winding of the film the danger of ignition of the film is greatly reduced 50 since it is not exposed to heat and sparks as is some times the case where the film is re-wound.

A further object of the invention is to provide a particular form of reel in which 55 the film may be conveniently wound toward the center.

Another object of the invention is to provide means for tightly winding the film, or other strip, from the periphery toward the 60 center of the reel.

Another object of the invention is to provide means for tightening the winding of the film upon the reel after a predetermined amount has been wound upon it. 65

A further object of the invention is to provide a strip winding machine in which the strip receiving reel can be readily removed from the winding mechanism.

A further object of the invention is to 70 provide positive means for driving the winding apparatus in correlation to the diameter of the spiral of strip which is being wound upon the reel.

Another object of the invention is to 75 provide a strip delivery reel to which the coiled strip of moving picture film, or other material, may be readily transferred from the film receiving reel.

A further object of the invention is to 80 provide a strip retaining device for the strip delivery reel which will overlie the exposed edges of the strip and prevent the same from displacement while the reel is being transported from place to place. 85

Other objects and features of the invention will more fully appear from the following description and the annexed drawings and will be pointed out in the accompanying claims. 90

A preferred embodiment of the invention is illustrated herein as adapted to re-

ceive the film delivered from the projecting apparatus of a moving picture machine.

In the drawings:

5 Fig. 1 is a side elevation of a winding machine, a portion of the standard being shown in section;

10 Fig. 2 is a detail view of the upper portion of the winding machine showing the mechanism which actuates the winding device in inoperative position so that the support for the reel may be swung into position to permit the removal of the reel;

15 Fig. 3 is a plan view of the winding mechanism and a portion of the mechanism for tightening the strip in the reel, a portion of the super-structure being broken away;

20 Fig. 4 is a vertical view, mainly in section, showing the upper portion of the reel elevating rod and the guiding means therefor with the means for releasing the reel elevating rod;

25 Fig. 5 is a detail view, partly in section, illustrating the connection of the drive shifting mechanism to the hub of the reel supporting means;

30 Fig. 6 is a sectional view on line 6—6, Fig. 5, looking downward upon the cap for the hub of the reel supporting means;

35 Fig. 7 is a detail view showing the adjustable and detachable extension of one of the levers for shifting the driving mechanism;

40 The present invention contemplates the provision of means for winding a strip, such as the strip of a moving picture film, as it comes from the moving picture machine, upon a reel in which spirals of the strip are laid upon the reel from the periphery toward the center, means being provided for progressively pressing and retaining the lower edge of the strip as it contacts with the base of the reel firmly 45 against the next outer spiral. This is accomplished by supporting the strip receiving reel upon a rotatable conical winding member in which the surface of the cone is of a suitable pitch which will cause its 50 surface progressively to contact with the lower edge of successive spirals as they are wound upon the reel and will act to press the lower edge of the spiral tightly against the next outer spiral and also to maintain 55 such pressure until the entire coil has been wound.

60 The invention further contemplates the provision of means for positively driving the conical member of the strip winding mechanism and automatically governing the speed of rotation of said conical winding member in correlation to the spiral which is being wound. To accomplish this purpose the reel supporting member is gradually 65 elevated as the spiral is being wound and

a mechanism is provided which is actuated by the upward movement of the reel supporting mechanism to shift a frictional driving mechanism toward the axis of the reel supporting means.

70 A preferred embodiment of the invention illustrated in the accompanying drawings comprises a frame having a base 1 from which rises an upright post 2 which is provided at its upper end with an overhanging arm 3 in parallelism with the base 1 of the frame and which serves to support a guiding device for the upper end of the elevating rod of the winding mechanism. A standard 4 is suitably secured to the base and extends upwardly therefrom and is provided with a socketed upper end which receives trunnions 5 of an upper section 6 in the form of a spider having laterally extending arms 7, preferably three 80 in number, provided at their ends with bifurcated bosses 8 having anti-friction rollers 9 which engage and support the base 10 of a conical winding member.

85 A bracket 11 pivotally mounted upon a screw or stud 12 in the standard 4 underlies one of the supporting arms 7 and normally holds the spider in horizontal position so that the base 10 of the conical winding member rotates in a horizontal 95 plane. When it is desired to remove the reel the bracket 11 is swung aside about its pivot 12 so as to permit the spider to be swung upon the trunnions 5 into substantially vertical position, permitting the reel 100 to be removed from the conical support as will hereinafter be more fully described.

105 The conical winding member comprises a shell 13 having a series of guiding slots 14 extending upwardly from its base and adapted to receive the arms 15 of the receiving reel spider so that the receiving reel spider may be raised upwardly while being rotated in unison with the rotation of the conical winding member. The arms 15 of the strip receiving reel are integral with a central disk 16 to which is affixed a hub 17 having a screw threaded central portion which engages a screw threaded elevating rod 18 which is fixedly secured in the hub of the spider 6 by a set screw 19. Both the lower and upper portions of the elevating rod 18 preferably are not screw threaded. The outer ends of the arms 15 of the reel desirably are integral with a flat annular rim 20 which is provided with tabs 21 which overlie and form guides for a flange 22 of a peripheral strip retaining means such as a ring 23 which is of the same or slightly greater height than the width of the film to be wound. The peripheral strip retaining ring 23, therefore, is rotatably mounted upon the rim 20 of the reel spider.

110 115 120 125 125 The peripheral strip retaining ring 23 de-

sirably is provided with arms 24 which extend inwardly a short distance and rest upon the arms 15 of the receiving reel spider. The arms 24, therefore, lie within the guiding slots 14 of the conical winding member when the reel is at the base of said conical winding member and remain in said slots during a portion of the elevation of the reel during the winding operation. When, however, the reel is raised sufficiently, the ends 10 of the arms 24 will not extend into the guiding slots 14 and when thus released the peripheral strip retaining ring 23 may be rotated independently of the rotation of the spider. Means are provided for producing 15 such relative rotation during the latter portion of the winding of the film for the purpose of tightening the spirals of the film within the reel as will hereinafter more fully appear.

As before stated the hub 17 of the reel is mounted upon and has screw threaded engagement with the stationary elevating rod 18 so that the rotation of the cone and reel 25 will cause a progressive upward movement of the reel. The end of the strip or film 25 is clamped at its end by means of a spring 26 against the inner wall of the peripheral strip retaining ring 23 and as the cone and reel are rotated the lower edge of the film 30 is pressed firmly against the inner wall of the peripheral strip retaining ring 23. As the winding progresses the reel is gradually raised by the screw threaded engagement of 35 its hub with the elevating rod and the margin only of the lower edge of the successive spirals of the strip are progressively pressed against the next outer spiral by the cone, so that the film is wound tightly from 40 the outside toward the center. By reason of the fact that the conical winding member engages the strip only at the margin of the lower edge as it progressively winds the spirals upon the reel from the outside 45 toward the center thereof contact with the face of the strip is avoided. Thus where a moving picture film is wound bearing a series of pictures injury to the pictures or scratching of the face of the strip is 50 prevented.

The upper end of the elevating rod 18 is journaled in a sleeve 27 (see Fig. 4), which desirably may be in the form of a pipe section having its upper end screwed into the 55 overhanging arm 3 of the main frame. The lower end portion of the pipe 27 is provided with a slot 28 adapted to permit the elevating rod to be removed laterally when it is desired to tilt the winding device for the 60 purpose of removing the reel. In order to confine the upper end of the elevating rod in its bearing a sleeve 29 is rotatably mounted upon the pipe 27 and is provided with a slot 65 adapted to be rotated into registry with the slot 28 when the upper end of the elevat-

ing rod is to be removed or to be rotated into a position to close said slot during the reeling operation.

In order to hold the sleeve 29 in place the lower end of the pipe 27 is provided with an 70 outwardly extending flange 30. As the progressive winding of the reel produces spirals of constantly but gradually decreasing diameter it is desirable that means shall be provided to produce a rotation of the winding mechanism in correlation to the decreasing diameter of the spirals of the strip or film. This is accomplished in the present invention by providing means governed by the elevation of the reel for shifting a frictional driving mechanism progressively toward the axis of the winding mechanism. In the preferred construction illustrated herein the hub 6 of the reel is provided with two concentric supporting members 31 and 32 which are rotatable within a relatively 80 stationary cap which is actuated by the elevation of the reel to shift the frictional driving mechanism.

As illustrated in Fig. 5 the cap comprises 90 two annular plates 33 and 34 which clamp between them the flange 35 of a cylindrical member 36 which encloses the outer supporting member 32; the disks 33 and 34 being secured together by suitable bolts or 95 screws. The cap is provided with a slot 37 to permit it to be swung laterally when it is desired to tilt the conical winding mechanism into position to permit the removal of 100 the reel.

The disk 34 of the cap is provided with 105 upwardly extending bosses 38 in which standards 39 are secured at their lower ends. These standards are pivotally connected at their upper ends to the lower ends of levers 40 which are fulcrumed about midway of their lengths upon a pivot 41 carried by a link or links 42 which are pivotally mounted upon their upper ends upon studs 43 carried by a bracket 44 having a sleeve 45 which is 110 slidably mounted upon the sleeve 29 which surrounds the pipe 27 forming the guide for the upper end of the elevating rod.

The spiral movement of the reel is translated through the lever 40 and other mechanisms hereinafter described into a movement which shifts a frictional driving wheel, which engages the base of the conical winding member, from the periphery toward the axis of said winding member in 115 correlation to the decreasing diameter of the spirals of the strip being wound. In order to maintain the proper correlation between the driving mechanism and the spirals of the strip being wound it is necessary to accelerate the movement of the frictional driving wheel toward the axis of the winding mechanism as the spirals of the strip progressively decrease in diameter. This is accomplished in the preferred embodiment of 120 125 130

the invention illustrated herein by the following mechanism. The upper ends of the levers 40 are pivotally connected to the lower end of a lever 46 which is fulcrumed upon a stud 47 on a carriage 48. The carriage is preferably mounted upon a track 49 and is provided with anti-friction rollers engaging each side of the track. As the lever 40 is raised by the elevation of the reel it moves 10 the lever 46 end-wise, thus moving the carriage along the track 49. At the same time the lever 46 swings about its pivot 47.

The lever 46 is provided with a laterally extending end 46* having a cam slot 50 in 15 which a stud 51, which forms the fulcrum of a lever 52, is slidably mounted. The lever 52 has a laterally extending end 52* which is provided with a stud which extends into a slot in the end portion of a link 53. 20 The opposite end of the link 53 is pivotally connected to a stud 54 upon the end of the extension 46* of the lever 46.

During the relative movement of the ends 46* and 52* of the levers 46 and 52 respectively the link 53 engages the pivotal stud 51 which forms the fulcrum of the stud 52 and forces it along the cam slot until at the 25 end of its movement it finally is lodged in an offset end of said slot. By thus shifting 30 the pivot 51 of the lever 52 the lever 52 is given a progressively increased end-wise movement which provides the necessary acceleration of the movement of the driving wheel toward the axis of the winding member when the relatively small spirals of 35 strip are being wound.

The lever 52 preferably is made adjustable in length in order to permit the driving wheel to be properly positioned in relation to the base of the winding member. As 40 illustrated herein the lever 52 is provided with an adjustable section 55 in the form of a rod which is slidably mounted in an upturned flange at the end of the lever 52 (Fig. 7). The end of the rod 55 is bent at 45 right angles to its axis and passes through a slot in the lever 52, a winged nut 55* upon the screw threaded end of the rod serving to clamp the same in adjusted position. 50 The opposite end of the rod 55 preferably is detachably connected by a bayonet and slot connection 56 to an arm 57 which is pivotally mounted upon a shaft 58 which is journalled in arms of brackets 59 having vertical sleeves which are slidably mounted upon 55 guide rods 60 carried by brackets 61 extending from the vertical standard 2 of the frame. A spring 62, connected at its lower end to one or both of the brackets 59 and at 60 its upper end to an arm extending from the side frame 2, tends normally to raise said brackets and thereby to move the frictional driving wheel toward the periphery of the base of the winding member as will herein- 65 after more fully appear.

Links 63, pivotally mounted at their upper ends upon the shaft 58, are connected at their lower ends to a shaft 64 on a slideable frame which serves to shift the frictional driving wheel radially in respect to the axis 70 of the rotatable winding member.

As illustrated herein the driving mechanism for rotating the winding member comprises a drive shaft 65 which is journalled at its outer end in a suitable bearing 66 carried by the upright standard 2 of the main frame and at its inner end in a boss 67 in the standard 4. The driving shaft has secured to it a belt pulley 68 and also has slidably mounted upon it a frictional driving wheel 69 preferably having a suitable tire 70 which engages the under face of the base 10 of the conical winding member. The frictional driving wheel 69 is slidably mounted upon the driving shaft, but is caused to rotate therewith by a feather carried by the hub of the wheel which engages a suitable slot 71 in the driving shaft. The hub of the pulley 69 is provided with an extension having an annular groove 72 which is engaged by a flange 73 at the end of a carriage which comprises a sleeve slidably mounted upon the driving shaft and having legs 75 and 76 which are provided at their lower ends with rollers 77 and 78 which travel upon guide rods 79 extending horizontally from the standard of the main frame to the standard 4 in parallelism with the driving shaft.

In the operation of the machine the upward movement of the reel acts through the non-rotatable cap 36 to raise the standards 39, thereby moving the lever 40 upwardly. As the upper end of the lever 40 is connected to the lever 46 it causes the latter to move end-wise during the first upward movement, thereby forcing the carriage 48 laterally, (to the left). At the same time the lever 40, acting through the link 42, raises the sleeve 45 until the latter engages the horizontal arm 3 of the frame. Further upward movement of the reel after the sleeve 45 has thus been seated against the arm 3 causes the link 42 to swing the fulcrum 41 of the lever 40 laterally, (to the left). This produces a continued movement of the carriage 48 to the left.

During these movements of the lever 46, the extension 46* of the lever 46 is swung downwardly carrying with it the end of the link 53 which is connected to it. As the main portion of the lever 46 approaches horizontal position the central portion of the link 53 engages the stud 51 which forms the fulcrum of the lever 52 and further pivotal movement of the lever 46 causes the link 53 to force said pivotal stud lengthwise of the slot 50 until it eventually reaches the end of said slot and enters the offset portion thereof. All of these movements of the

lever 46 and carriage 50 causes the lever 52 to move end-wise as well as to rock about its pivot 51. The end-wise movement of the lever 55 depresses the brackets 59, thus forcing downwardly upon the link 63. This downward movement of the brackets 59 causes the links 63 to shift the carriage along its track toward the right, thereby forcing the driving wheel 69 toward the axis of the 10 winding member.

The variable movement of the driving wheel toward the center of the winding member, produced by the mechanism above described, causes the winding member to rotate with a speed which is correlated to the speed of delivery of the strip being wound which, it will be understood, is delivered at a constant speed.

At the end of the winding operation the 20 carriage 48 and levers 40, 46 and 52 are in substantially the position illustrated in Fig. 2 with the axes of the levers 40 and 46 in substantial alinement. At this time the hub of the reel has passed out of engagement 25 with the screw threads upon the elevating rod and rotates upon the smooth upper end of the rod. The reel is then ready for removal from the machine. In order to accomplish this the hub cap is swung upwardly about the pivotal connection between 30 the standards 39 and the lower arms of the lever 40 into the position illustrated in Fig. 2, the slot 37 permitting such movement. The sleeve 29 is then rotated to bring its slot 35 into alinement with the slot 28 in the journal which supports the upper end of the elevating rod, so that the upper end of the elevating rod can be moved laterally out of its journal. The bracket 11, which engages 40 one of the arms 7 of the supporting spider for the winding mechanism, is then swung aside and the conical winding member tilted upon its supporting trunnions 5 to an inclined or substantially horizontal position, 45 whereupon the reel is lifted from the end of the conical winding member and transferred to a delivery reel.

In order to replace a new reel upon the machine the set screw 19 desirably is unscrewed and the elevating rod removed from the winding mechanism and its lower end screwed a short distance into the new reel. The reel is then placed upon the conical winding member and the end of the elevating 55 rod again seated and clamped by the screw 19 and the conical winding member restored to its vertical position. The rod 55 of the lever 52 is then coupled with the arm 57 by manipulation of the coupling member 56 and the device is then prepared to renew the reeling operation.

It is sometimes desirable to tighten the winding of the film after a considerable portion of the film has been wound. This is 60 accomplished in the present invention by

causing a differential rotation of the peripheral strip retaining ring 23 which engages the outer spiral of the strip relatively to the conical winding member after a predetermined portion of the strip has been 70 wound. It will be remembered that the peripheral strip retaining ring 23 is rotatably mounted upon the disk 20 within the keepers 21. The differential rotation is imparted to this peripheral strip retaining 75 ring by means of a pulley having a frictionally driven rim 80 which engages the periphery of the ring 23. The pulley rim 80 is mounted upon a series of radial plungers 81 slidably mounted in 80 guideways 82 in a cylindrical pulley 83 having a hub 84 which is slidably feathered upon a shaft 85 which is journalled in suitable bearings, (not shown). Springs 86 located in the guideways 82 serve to force 85 the plungers 81 outwardly into frictional engagement with the pulley rim 80. The shaft 85 is provided with a suitable sheave or pulley which is engaged by a belt 87 which passes over idler pulleys 88 and is 90 driven by a pulley 89 upon the main driving shaft 65.

During the early part of the winding movement the arms 24 which are connected to the ring 23 are located in the slots 14 in the conical winding member and the ring 23 is rotated in unison with the conical member irrespective of any action of the rim 80 of the tension pulley. During this time the tension pulley 80 rotates upon the periphery of the ring without having any influence upon it. When, however, the reel has been elevated sufficiently to cause the arms 24 of the reel to pass out of the slots 14 in the conical winding member the tension pulley 80 will rotate the peripheral strip retaining ring 23 somewhat faster than the rotation of the winding cone, thereby imposing a greater tension upon the wound film during the latter portion of the winding movement. By reason of the frictional engagement between the plungers 83 and the rim 80 of the tension pulley any desired amount of slippage may be given to the rim 80 of the driving pulley so that a proper amount of tension may be applied to the film when under the influence of this tension mechanism. By reason of this construction a tight winding of the strip is insured.

It will be understood that the embodiment of the invention disclosed herein is illustrative and is not restrictive; that various modifications in construction and arrangement of parts may be made within the spirit and scope of the invention, and that the strip receiving reels and winding mechanism is adapted to be utilized to wind various devices other than strips of moving picture film and that the strip delivery reel particularly adapted to the usages herein 130

described may be employed in other relations within the spirit and scope of my invention.

Having thus described my invention, what I claim as new, and desire to secure by Letters Patent, is:

1. A strip winding machine comprising a strip receiving reel having a base and a peripheral strip retaining means, means for producing a flat winding of the strip within said reel from said retaining means toward the center thereof including means for progressively engaging margin only of the edge of the strip as it contacts with the base of said reel and acting to compress and hold the spiral being wound against the next outer spiral without engaging the face of the strip, whereby injury to the surface of the strip is avoided.
2. A strip winding machine comprising a rotatable strip receiving reel having a base and a peripheral strip retaining means, means for producing a flat winding of the strip within said reel from said retaining means toward the center thereof including means for progressively engaging the edge of the strip as it contacts with the base of said reel and acting to compress and hold the spiral being wound against the next outer spiral, means for producing relative axial movement between said reel and strip engaging means, and means operable by said relative axial movement for controlling the speed of rotation of said winding means in correlation to the diameter of the inner spiral being wound.
3. A strip winding machine comprising a strip receiving reel having a base and a peripheral strip retaining means, means for winding the strip within said reel from said peripheral retaining means toward the center thereof including means for progressively engaging the edge of the strip as it contacts with the base of said reel and acting to compress and hold the spiral being wound against the next outer spiral and means operable after a predetermined amount of the strip has been wound to apply tension upon the spirally wound strip during the remaining portion of the winding operation.
4. A strip winding machine comprising a strip receiving reel having a base and a peripheral strip retaining means, a rotatable conical winding member located within said reel acting to engage progressively the lower edge of the strip being wound as it contacts with the base of said reel and to compress and hold the spiral being wound against the next outer spiral and means for causing relative movement axially between said reel and said winding member, as the strip is being wound, in correlation to the diameter of the inner spiral.
5. A strip winding machine comprising a strip receiving reel having a base and a relatively rotatable peripheral strip retaining means, a rotatable conical winding member located within said reel acting to engage progressively the lower edge of the strip being wound as it contacts with the base of said reel and to compress and hold the spiral being wound against the next outer spiral, means for causing relative movement axially between said reel and said conical winding member, as the strip is being wound, in correlation to the diameter of the inner spiral and tensioning means comprising a positively driven frictional pulley engaging said peripheral strip retaining means and acting to increase the rotation of the winding means thereby increasing the tightness of the winding of the strip.
6. A strip winding machine comprising a strip receiving reel having a base and a relatively rotatable peripheral strip retaining means, a rotatable conical winding member located within said reel acting to engage progressively the lower edge of the strip being wound as it contacts with the base of said reel and to compress and hold the spiral being wound against the next outer spiral, means for causing relative movement axially between said reel and said conical winding member, as the strip is being wound, in correlation to the diameter of the inner spiral and tensioning means comprising a positively driven frictional pulley engaging said peripheral strip retaining means and acting to increase the rotation of the winding means thereby increasing the tightness of the winding of the strip.
7. A strip winding machine comprising a strip receiving reel having a base and a relatively rotatable peripheral strip retaining means, a rotatable conical winding member located within said reel acting to engage progressively the lower edge of the strip being wound as it contacts with the base of said reel and to compress and hold the spiral being wound against the next outer spiral, means for causing relative movement axially between said reel and said conical winding member, as the strip is being wound, in correlation to the diameter of the inner spiral and tensioning means comprising a positively driven pulley having a frictionally driven rim engaging said peripheral strip retaining means and acting when the strip receiving reel is raised to a predetermined height to increase the rotation of the peripheral strip retaining means relatively to said cone and thereby to increase the tension upon said strip.
8. A strip winding machine comprising a strip receiving reel having a skeletonized base provided with arms and a peripheral rotatable strip receiving means having short arms registering with those of said base, a rotatable conical winding member having

- guiding slots to receive the arms of said base located within said reel and acting to engage progressively the lower edge of the strip being wound as it contacts with the base of said reel and to compress and hold the reel being wound against the next outer spiral, means for causing relative movement axially between said reel and said conical winding member, as the strip is being wound, in correlation to the diameter of the inner spiral and tensioning means operable to impart a differential rotation to the peripheral strip retaining means when its arms have become disengaged from the guiding slots in said cone whereby the tension upon the spirals on the reel will be increased during the final winding movement.
9. A strip winding machine comprising a strip receiving reel having a skeleton base and a peripheral strip retaining means, a rotatable conical winding member having guideways to receive the skeleton base of said reel and acting progressively to engage the lower edge of the strip being wound and hold the same against the next outer spiral and means for progressively moving said reel axially of said winding member in correlation to the diameter of the spiral being wound.
10. A strip winding machine comprising a strip receiving reel having a skeleton base, a hub and a peripheral strip retaining means, a rotatable conical winding member having guideways to receive the skeleton base of said reel and acting progressively to engage the lower edge of the strip being wound and to hold the same against the next outer spiral, a stationary rod having screw threaded engagement with said hub acting to move said reel axially of said conical member in correlation to the diameter of the spiral being wound.
11. A strip winding machine comprising a strip receiving reel having a skeleton base, a hub, a peripheral strip retaining means, a rotatable conical winding member having a base and provided with upwardly extending guideways to receive the skeleton base of said reel, said cone acting to engage progressively the lower edge of the strip being wound as it contacts with the base of said reel, a rod mounted axially of said winding member having a screw threaded portion engaging the hub of said reel, a driving pulley, slidably mounted on said driving shaft and rotatable thereby, frictionally engaging the base of said winding member and means for progressively moving said driving wheel toward the axis of said winding member in correlation with the decreasing diameter of the spiral being wound.
12. A strip winding machine comprising a strip receiving reel having a skeleton base, a hub, a peripheral strip retaining means, a rotatable conical winding member having a base and provided with upwardly extending
- guideways to receive the skeleton base of said reel, said cone acting to engage progressively the lower edge of the strip being wound as it contacts with the base of said reel, a rod mounted axially of said winding member having a screw threaded portion engaging the hub of said reel, a driving shaft, a driving pulley, slidably mounted on said driving shaft and rotatable thereby, frictionally engaging the base of said conical member and means for progressively moving said driving wheel toward the axis of said winding member in correlation with the decreasing diameter of the spiral being wound.
13. A strip winding machine comprising a strip receiving reel having a skeleton base, a hub, a peripheral strip retaining means, a rotatable conical winding member having a base and provided with upwardly extending guideways to receive the skeleton base of said reel, said cone acting to engage progressively the lower edge of the strip being wound as it contacts with the base of said reel, a rod mounted axially of said winding member having a screw threaded portion engaging the hub of said reel, a driving shaft, a driving pulley, having a hub, slidably mounted on said driving shaft and rotatable thereby, frictionally engaging the base of said conical member and means for progressively moving said driving wheel toward the axis of said winding member in correlation with the decreasing diameter of the spiral being wound.
14. A strip winding machine comprising a strip receiving reel having a skeleton base, a hub, a peripheral strip retaining means, a rotatable conical winding member having a base and provided with upwardly extending guideways to receive the skeleton base of said reel, said cone acting to engage progressively the lower edge of the strip being wound as it contacts with the base of the reel, a rod mounted axially of said winding member having a screw threaded portion engaging the hub of said reel, a driving shaft, a driving pulley, slidably mounted on said driving shaft and rotatable thereby, frictionally engaging the base of said winding member and means operable by the vertical movement of said reel to force said driving pulley progressively toward the axis of said winding member whereby the speed of rotation of said winding member may be correlated to the speed of rotation of the spiral being wound.
15. A strip winding machine comprising a base, a jointed sectional standard rising therefrom, a conical strip winding member rotatably mounted upon the upper section of said standard, means for rotating said winding member, reel supporting means and

means operable to permit the upper section of said standard to be swung toward horizontal position to facilitate the removal of said reel.

- 5 16. A strip winding machine comprising a base, a jointed sectional standard rising therefrom, a conical strip winding member rotatably mounted upon the upper section of said standard, means for rotating said
- 10 winding member, a reel supporting rod hav-

ing a screw threaded section adapted to engage the hub of a strip receiving reel, and a smooth section extending axially of said winding member into said standard and means for detachably clamping said rod in 15 said standard, whereby said rod may be released from said standard.

In testimony whereof, I have signed my name to this specification.

MYLES F. MORAN.
